UNITED STATES PATENT OFFICE

JOHN V. BOX, OF LOS ANGELES, CALIFORNIA, ASSIGNOR OF ONE-HALF TO CHARLES A. DAILEY, OF TORRENCE, CALIFORNIA

SAFETY DEEP WELL PUMP ASSEMBLY

Application filed October 15, 1928. Serial No. 312,443.

This invention relates to the art of lowering sucker rods into and pulling them out of pump tubing in deep wells.

Many of such wells are being sunk to six thousand feet and more, and the pumps for pumping the oil from great depths are operated by sucker rods connected to polish rods that work through stuffing boxes connected to the tops of the pump tubing through which the oil is pumped; and in case the sucker rod has to be pulled in order to get at the sucker or the standing valve, it is necessary to remove the stuffing box and to pull out the sucker rod, and to disjoint it as the pulling proceeds, and to stand the disconnected lengths of the sucker rod in the derrick.

This operation requires the use of elevators to take hold of the rod and pull it up, and also the use of slips to hold the rod from falling back into the pump tubing when the lengths are being unscrewed at the top and deposited in the derrick.

The weight of the sucker rod suspended in the pump tubing is very great, and powerful means are required to handle the same; and great loss sometimes occurs from breakage of the support at either the up or down movement of the sucker rod, and also from dropping the rod at the times of changing from support by the slips to support by the elevators, and vice versa.

An object of this invention is to provide means which can be applied to and removed from the top of the pump tubing while the sucker rod is suspended in the tubing; and which means, when so applied, will afford a sufficiently strong support for the great length of sucker rod below, and which will hold the sucker rod supporting slips, and will allow such slips to be withdrawn upward by the joints of the sucker rod sufficiently to allow such joints to pass the slips; and which also will be susceptible of allowing the sucker rod valve cage to pass up satisfactorily without any likelihood of breaking the equipment at the final withdrawal of the sucker valve cage from the tubing.

Another object of the invention is to improve the means for applying the slips to the

sucker rod for its support and for releasing the slips from their support and also to allow the sucker rod to run up freely between the slips as the sucker rod is being pulled, and to make provision whereby the slips readily and conveniently catch the sucker rod when it is lowered for that purpose.

An object of this invention is to provide a support that can be, with perfect safety, applied to the pump tubing while the sucker rod is suspended therein and that will perfectly serve to uphold the sucker rod at each standing period that arises from time to time during the withdrawing operation until the last joint is removed; and which will be lifted by the valve-cage when the cage is brought against it by the hoisting machinery at the close of the withdrawing operation, and can then be safely withdrawn while the rod is suspended from the derrick.

Objects of the invention are compactness, and strength, ease, speed and certainty of operation, and ease of assembly and installment.

An object of the invention is to simplify the work of installing or removing the sucker rod supporting means with regard to the pump tubing; and in this respect the invention broadly includes a sucker rod supporting device comprising supporting elements having side gaps so that said supporting elements may be applied to and removed from the pump tubing and sucker rod while the sucker rod is suspended in the tubing.

The invention includes the parts, the assembly of parts and the combination of parts by which this advantage is secured and includes more particularly a supporting head having a side gap, a spider having a side gap, and adapted to be seated in the supporting head with the gaps disaligned or staggered relative to each other, and it also includes slips and a mounting therefor, said mounting and slips being constructed to provide a side gap adapted to receive the sucker rod and to so wedge thereupon as to spread the jaws and the slips apart when the jaws are forced onto the sucker rod with the rod in the gap between said jaws. The sucker rod seats of the slips flare upwardly so that when the slips are out of the spider and tilted and moved laterally for

the purpose, the sucker rod will wedge upon the slips so that the jaws will be spread apart thereby to allow the slips to be removed from the sucker rod.

8 Other objects, advantages and features of invention may appear from the accompanying drawings, the subjoined detailed description and the appended claims.

10 The accompanying drawings illustrate the invention.

15 Figure 1 is an axial section on plane indicated by line $\alpha 1-\alpha 8$, Figs. 2, 4 and 5, showing the device and pump tubing supported by a well casing, and looking in the direction of the arrows; the lower section of the sucker rod with valve cage attached is shown in the upper joint of the pump tubing, having been drawn up out of the working barrel, not shown, and supported by the slips and ready 20 to be drawn up to jar the spider from its seat preparatory to removal of the support and valve.

25 Fig. 2 is a fragmental side elevation of the installation shown in Fig. 1.

30 Fig. 3 is a side elevation of the slips and the slip holder detached; the latter being partly in section.

35 Fig. 4 is a plan of the spider in the supporting head.

40 Fig. 5 is a plan of the slips and slip holder detached and fully closed; the top of the housing for the shanks of the slip holder being cut away on the horizontal plane indicated by line $\alpha 5-\alpha 5$, Fig. 3.

45 Fig. 6 is a perspective view of one member of the slip holder detached.

50 Fig. 7 is a view of one of the slips in place on one member of the slip holder which is shown detached from its mate and housing.

55 Fig. 8 is a fragmental view of the device shown in Fig. 1 with the valve cage supporting the slips and the spider, which latter is almost withdrawn from the casing head that is shown in vertical mid-section, on the plane indicated at line $\alpha 1-\alpha 8$, Figs. 2, 4 and 5.

60 Fig. 9 is an enlarged fragmental sectional detail of the joint between the supporting head and the spider in the position indicated in Fig. 1.

65 Fig. 10 is a plan view of the spider detached.

70 Fig. 11 is a view of the slip supporting spider detached.

75 Fig. 12 is an elevation of the outer side of one of the slips.

80 The sucker rod 1 and the tubing 2 are of any approved form, and a tubing supported head 3 provided with an externally threaded neck 3' and an internal spider supporting shoulder 3'' is connected to the tubing by suitable means as the internally threaded collar 4, screwed onto the tubing 2, and resting on the casing head 4a carried by the casing 4b, and into which collar the neck is screwed.

85 Said head 3 has horizontal inwardly di-

minishing open spring and ball ways 5 provided with yielding spider holders in the form of balls 6 that are of larger diameter than the inner ends of the ways 5 and that are inwardly pressed by springs 7 held in place by cotter-pins 8, and that project inwardly from the walls of the head to engage the spider 9 which has seats 10 into which the balls are yieldingly forced by the springs 7 so that the spider is held seated in the head under normal working, but may be jarred up by the valve-cage at the final removal of the sucker rod.

90 The spider 9 is seated on the annular shoulder 3'' of the head and has a downwardly diminishing bore 11 to receive downwardly tapered slips 12, 12' which are provided with longitudinally channelled wickers 13, adapted to fit around and engage the sucker rod 1 and hold it from downward movement when 95 the slips are in place.

100 The slips are connected to handling means comprising jaws, and shanks, a housing in which the shanks are positioned, and a handle fixed to the housing. With this in view each slip is provided in a plane normal to its axis with an external arcuate dove-tail groove 14 to fit on arcuate dove-tail slip carrying runners 14' of the jaws 15, 15' carried by shanks 16 and 16', that are pivoted on a pivot pin 17 and end in socketed terminals 18, 18' which are yieldingly held apart by a spring 19 to yieldingly hold the slips toward each other so that the wickers will engage the rod 1.

105 The spider bore 11 at its most contracted cross-section is of greater diameter than the boxes of the sucker rod joints so that said joints may pass freely down and up through the spider as the sucker rod is being lowered or pulled. The sucker-rod joints are of less diameter than the lower end of the assembled slips and the sucker rod boxes are of greater diameter than the combined rod gripping channels of the wickers so that when the sucker rod is being pulled, the boxes will engage the slips to force them up out of said downwardly diminished bore of the spider, thus to displace the slips sufficiently to allow them to be spread apart when the slips are above the spider; and by this arrangement the sucker rod is allowed to pass up through the spider without any likelihood of breakage.

110 The shanks are pivoted by the pin 17 to a housing 20 that is provided with a handle 21 in the form of a stirrup that is set downwardly aslant and extends below the level of the housing and beyond the end thereof for convenience in handling the slips and especially in withdrawing the wickers from the sucker rod by an upward pull on the handle that will yank the slips off the rod with a wedging motion, provision for which is made by shaping the slips above and below the wickers 115

with inwardly sloping top and bottom recesses 22 and 23.

The supporting head 3 is provided in one side with a gap 24 wide enough to accommodate the sucker rod so that said head may be placed onto and taken from the tubing 2 and collar 4 thereon, without interference with the sucker rod.

The spider 9 is provided with a vertical 10 radial cleft or sucker rod side gap 25 for a like purpose so that the parts may be assembled and disassembled, by sidewise movement while the sucker rod is in the tubing for pump operation or suspended by the elevator 26.

The slips are provided at their upper ends 20 with screw head receiving recesses 29, and the jaws 15, 15' are provided with threaded seats 30, into which are screwed the screws 31 having heads 32, so that when said screws 25 are tightened, the slips are secured against turning in the jaws 15, 15'.

The outer ends of the jaws terminate in 25 sucker rod side gap faces 33 that are outwardly divergent and that are tangent to the path through which such faces move when the jaws are swung upon the pivot 17. The faces 34 of the sucker rod gap of the slips 12, 12' extend in planes alined with the faces 30 33 and likewise tangent to the path of such faces when the jaws are swung apart by their movement on the pivot 17. By this arrangement the slips are adapted to be snapped onto the sucker rod by adjusting the device shown 35 in Fig. 5, with its gap between the faces 33 and 34 presented toward the sucker rod, and such device is then shoved forward so that the faces 33 and 34 will impinge upon the sucker rod, and therefore the momentum of 40 the device will cause the jaws to be forced open by the impingement of said faces with the sucker rod; the wedging action serving to compress the spring 19 until the sucker rod comes into place inside the wickers.

45 The rear jaw faces 35 between the wickers and the pivot 17, preferably fit together when the jaws are closed by the pressure of said spring 19.

The divergent faces 34 of the slips form 50 inward extensions of the divergent faces 33 of the jaws and the meeting faces 35 of the jaws between the slips and the jaw pivot 17 do not have sufficient spread to pass the sucker rod, so that when the gap 36 has passed the sucker rod, the sucker rod slips come to a stop with the sucker rod in the wicker bore 32.

To apply the invention to a pump while the sucker rod is in the tubing, the supporting head having the gap 24 therein will be brought into position with the gap in position to receive the sucker rod, and will then be brought into alinement with the tubing and screwed into the collar 4. Then the 65 spider 9 is in like manner brought into posi-

tion with the gap 25 thereof directly opposite the gap 24 in the supporting head and then the spider is allowed to seat itself by gravity. Then the slips are brought into position as indicated in Figs. 1, 2 and 8 and the work of lowering the sucker rod joint by joint is proceeded with in an obvious manner, the slips serving to support the sucker rod when such support is needed.

To lower the sucker rod, the same will be 70 suspended from the elevator and the slips will be opened by spreading apart the ends of the jaws 15, 15', and then the elevator will be lowered in the usual manner to lower the rod.

To remove the sucker rod, the same is withdrawn joint by joint until the cage c strikes the spider, thus forcing it up from the supporting head. The spider may then be removed sidewise the vertical sucker rod gap 25 allowing it to be drawn off of the sucker rod and when desired the supporting head may be unscrewed and taken off sidewise in like manner.

In this way the necessity of pulling the rod 90 to install the head and the spider is obviated, and the spider and the spider supporting tubing head may be shifted from well to well as sucker rod pulling operations are required, and perfect safety against dropping the rod 95 is secured.

I claim:

1. An assembly of the character set forth comprising a head adapted to be secured to pump tubing and provided with a seat having an internal horizontal shoulder and also provided in one side with a gap adapted to admit a sucker rod; a spider seated in said seat and provided with a downwardly reduced slip seat and having in one side a vertical slot to pass a sucker rod to the slip seat; slips adapted to seat in the slip seat of the spider and having wickers adapted to fit upon a sucker rod; said slips also being provided at one side of the wickers with meeting faces and with divergent faces at the other side of the wickers; and jaws in which such slips are mounted; said jaws being adapted to be closed and having divergent extensions of the divergent faces of the slips, and forming guides to receive between them a sucker rod for the purpose of spreading the jaws apart by contact with the sucker rod when the closed jaws are moved horizontally to position above the spider to enclose the sucker rod in the slips. 110

2. In a well pump assembly, a head adapted to be connected to the top of pump tubing and provided in one side with a vertical cleft adapted to pass a sucker rod, said head being provided with a seat for a spider; a spider having a downwardly reduced seat to receive sucker rod slips and provided in one side with a vertical slot adapted to pass a sucker rod when the same is suspended in the pump tubing so that the top of such tubing may be 120 125 130

equipped with a seat to seat slips for supporting such sucker rod.

3. In a well pump assembly, slips having wickers to engage a sucker rod; jaws pivoted together and connected to said slips respectively; said jaws and slips being provided with vertical guiding faces open to pass a sucker rod when the closed jaws with slips therein are moved to cause such guide faces to impinge upon the sucker rod between them.

4. In a well pump assembly, slips having wickers to engage a sucker rod; jaws pivoted together and connected to said slips respectively; said jaws and slips being provided with vertical guiding faces open to pass a sucker rod when the jaws with slips therein are moved to cause such guide faces to impinge upon the sucker rod between them; and handling means to which the jaws are pivoted.

5. In a well pump assembly, slips having wickers to engage a sucker rod; jaws pivoted together and connected to said slips respectively; said jaws and slips being provided with vertical guiding faces open to pass a sucker rod when the jaws with slips therein are moved to cause such guide faces to impinge upon the sucker rod between them; a housing partly enclosing said jaws; and a handle extending downwardly aslant away from said housing.

In testimony whereof, I have hereunto set my hand at Los Angeles, California, this 9th day of October, 1928.

JOHN V. BOX.
